RECORD CONTROLLED MACHINE

Robert L. Houston, New York, N. Y.

Application April 25, 1930, Serial No. 447,351

14 Claims. (Cl. 235—61.6)

This invention pertains to record controlled machines which register or accumulate the data or designations recorded, such as by perforations, upon record cards. The record card may contain a plurality of independent items or designations in each column in columnar alignment, the data desired being recorded thereupon by means of perforations. These perforations are read and registered or accumulated by the machine.

The perforated record card need not be larger than those now used and known to the art and yet this size of card is capable of recording at least double the amount of data customarily recorded upon these cards. This is accomplished by utilizing the spaces between the regular perforation positions of the card for perforation positions and for this reason these spaces may be termed interspaced positions although either set of perforation positions is interspaced with respect to the other. The machine described herein is capable of reading and recording or accumulating the perforations in regular position and also the interspaced perforations in a single passage of the card through the machine. Again, either the regular or the interspaced perforations may be read without reading the other record in a single passage of the card through the machine as desired.

It is an object of this invention to read and register one or more independent perforated items or designations located in the same column or series of columns of a record card wherein the additional set or sets of perforation positions are interspaced between other or the normal perforation positions of the card and are in columnar alignment with these positions.

Another object is to provide mechanism for reading and registering or accumulating or otherwise utilizing one or more sets of independent designation positions located in columnar alignment within the same column or columns of a record card during a single cycle of operation of the machine which cycle is measured by the card passing once through the machine.

It is also an object of the invention to provide mechanism for reading one or more independent designations in columnar alignment within a single column of a record card by means of a single sensing element.

Another object is to provide means to distribute the item or designation set up by the regular perforation and the designation of the interspaced perforation during a single cycle of operation to independent recording means or accumulator orders and utilizing a single sensing element.

A further object is to provide means enabling each of the plurality of perforation designations in one or more columns of the card to be distributed to accumulators so that each perforation is registered as a separate digit of a single 5 digit number or registered upon adjacent accumulators, each of which represents or records a separate digit of a multi-digit number.

The invention will be more apparent from the following description taken in connection with 10 the accompanying drawings in which:

Figure 1 is a perspective view of a record card feeding mechanism which feeds the perforated cards one at a time into the machine and into operative relation with the record perforation 15 sensing means and associated mechanism which are also shown.

Figure 2 represents a portion of a record card perforated in accordance with the well known 20 digit index system.

Figure 3 represents a portion of the same card shown in Figure 2 but having a second set of 25 digit index perforations located in the interspaced positions between the regular perforation positions.

Figure 4 shows a diagrammatic view of the perforation sensing mechanism and a wiring diagram for reading three columns of a perforated record card having regular and interspaced perforations, as shown in Figure 3, with accumulators for registering the value or digit represented by the perforations.

Figure 5 shows a diagrammatic view of the perforation sensing mechanism and a wiring diagram for reading two columns of the perforated record card in which the perforations in a single column of the card are distributed to register or accumulate as separate digits of a compound number.

Figure 6 is an enlarged view of distributing 40 commutators, surface developments of which are shown in Figure 4, and with brushes contacting with the commutators.

Figure 7 is an enlarged view of a shunt control commutator, a surface development of which is 45 shown in Figure 4.

Figure 8 shows a plug-in cord by means of which any designation in any column of the card may be recorded on any desired accumulator.

One of the systems of perforating record cards 50 heretofore widely used for controlling accounting machines has used a method of recording data upon perforation cards known as a digit index system. This system provides a plurality of columns of record positions and each column has at 55

least nine spaced perforation positions. Such cards were adapted to receive a single perforation in each column which represented the desired recorded data and the machines controlled by 5 the cards are capable of reading only one such perforation. Obviously a card upon which more than a single record perforation could be recorded in each column of perforation positions and a machine which is capable of reading a plurality 10 of perforations of recorded data in each column has the advantage that twice as much data may be recorded upon a single card of equal size and having an equal number of columns of perforation positions as could heretofore be recorded 15 upon the card.

The construction by which I accomplish these results is shown in the drawings in which Figure 1 shows a plurality of cards 1 placed in vertical position upon a platform 2 and advanced along 20 this platform by a backing plate 3. This backing plate retains the cards in vertical position and also advances them along the platform 2 by means of the cables 4 passing over the pulleys 5 and upon the end of each cable is suspended a 25 weight 6 to bring the cards into the path of the card feeding mechanism.

The card feeding device consists of a bar 10 which is caused to reciprocate in the guides 11 through the connecting rod 12 connecting the 30 reciprocating bar 10 with the eccentric 13. The bar 10 engages the first card upon the platform and feeds it into feed rollers to be described. This card feeding mechanism is merely illustrative of any method or means of feeding the cards 35 into the machine.

The feeding means directs the card in-between the feeding rollers 15 which feed the card past a series of spaced sensing elements 16 supported upon a bar 17 of insulating material so that each 40 sensing element is insulated from all of the other elements. These sensing elements are in direct alignment with the columns of perforation positions upon the card and are adapted to project through a perforation upon the card, irrespective 45 of the position which is perforated and thereby establish an electrical circuit as will be more fully described.

The sensing elements 16 are in contact with a metallic roller 19, so long as there is no card between the roller and the elements. The metallic roller 19 is mounted upon and insulated from a shaft 20. A brush 21 is always in contact with the roller 19 to apply an electrical potential thereupon during the desired part of the cycle as 50 will be more fully explained. The roller 19 in addition to being part of electrical circuits to be described, also rotates and serves as a card feeding roller in conjunction with the rollers 22 mounted upon the shaft 23, between which rollers 55 19 and 22 the card is adapted to pass. Upon the same axis with the roller 19 and secured upon and insulated from the same shaft 20, is a metallic ring 25 separated from the roller 19 by a narrow strip of insulating material 26.

60 A brush 27 is in contact with the metallic ring 25 to establish an electrical contact therewith. The roller 19 may be driven by any suitable driving mechanism, such as the belt and pulley 28. A gear 30 is keyed to the shaft 20 which gear 70 meshes with a second gear 31 keyed to shaft 23, and this second gear 31 meshes in turn with a third gear 32 keyed upon a shaft 33. These gears are adapted to drive the respective shafts 20, 23 and 33 at the same speed.

75 In order to better understand the operation of

the machine, a brief description will be given of a perforated record card as heretofore used, and the perforated record card having a plurality of perforations in each column in columnar alignment. Figure 2 shows a record card 35 having a 5 plurality of columns 36 of perforation positions utilizing the digit index system which is much used today for the recording of data thereon and in Figure 3 is shown the card 1 also using the digit index system but having a plurality of 10 perforations in each column. The cards are identical in size and have an equal number of columns of perforation positions which are numbered from 0 to 9 for convenience in visual reading of the designations or items recorded on the 15 card. A perforation (Figure 2) is punched in the perforation position in each column to represent the data desired to be recorded upon the card. The last three columns of the card have perforations 37a, 37b and 37c in their respective 20 columns 36a, 36b and 36c to record the respective numerals 9, 5, 8 giving the number 859 as is well known.

The perforated record card 1 shown in Figure 3 also contains a plurality of columns 40a, 40b, 40c, 25 etc., of spaced perforation positions in which the same data recorded on card 35 of Figure 2 is recorded thereupon by perforating the last three columns with the perforations 41a, 41b and 41c in the positions 9, 5 and 8 to record the number 30 859. In addition to the data recorded upon the card shown in Figure 2, the card 1 of Figure 3 utilizes the spaces 42 between the perforation positions designated by the numerals, as additional perforation positions to record additional 35 data in each column. It is to be noted that all the perforation positions in each column are in alignment. These spaces in between the numbered or regular perforation positions are for convenience designated as interspaced positions. 40 The last three columns of the card, shown in Figure 3, are perforated in interspaced position to record the number 837 as will be explained more fully hereinafter.

It will be observed that the interspaced number 45 8 is directly above the perforation position bearing the numeral 8 although it is within the scope of the invention to have the interspaced record numbers immediately in the space beneath the numbered perforation positions instead of as 50 shown and described above. Obviously too the perforation records in each column of the card need not be limited to two perforation records provided the card is large enough to take additional interspaced records. The perforations also 55 may be small enough to enable additional ones to be spaced between the regular perforations. It will be observed, therefore, that with only one set of interspaced positions, there are provided eighteen perforation positions which may be used 60 to provide a plurality of sets of perforation positions, and each set is adapted to record one item or number.

It will be observed that the card shown in Figure 3 in the last perforation column 40a has a 65 perforation 41a to record thereon the numeral 9 in the numbered perforation position and a perforation 43a to record the numeral 7 positioned in the interspaced position 42 between the numbered perforation positions 6 and 7. The next column 40b is perforated at 41b and 43b to record 70 5 and 3 and the next column is perforated at 41c and 43c to record 8 and 8. The card 1 has, therefore, twice as much data recorded thereupon as card 35 shown in Figure 2, which results in an 75

obvious saving of perforation card material and, in addition thereto, the double amount of data recorded upon card 1 may be filed in cabinets of no greater size than the cabinets utilized for the card 35, shown in Figure 2, which have but one-half as much data recorded thereupon.

A diagrammatic view is shown in Figure 4 of the mechanism by which the perforations in the record card 1 are sensed and registered and inasmuch as these mechanisms are identical for each column of perforation positions, the mechanism for one column only will be described. The circuits and mechanisms for sensing and registering or accumulating perforations for three columns of perforation positions are shown on the drawings to simplify the disclosure.

The perforations in the card are sensed by the brushes or sensing elements 16 projecting through the perforations as the card is fed between the metallic roller 19 and the sensing elements. In projecting through the perforations, the sensing elements contact with the roller 19 to establish electrical contact therewith. These sensing elements are also in contact with the roller 19 when there is no card between the roller and sensing elements or brushes and therefore a circuit is provided which automatically closes the electrical circuit to the roller 19 whenever a card is fed between the roller and the brushes and breaks the circuit when the card has passed by the brushes or sensing means.

This automatic controlling circuit consists of the metallic ring 25 which is insulated from the roller 19 by the insulating ring 26 (Figure 1). The brush 27 remains constantly in contact with the ring 25 and is connected to a source of electrical potential 50 by means of the conducting wire 51. The last sensing element 18 mounted upon the insulated bar 17 (Figure 1) is also adapted to contact with the conducting ring 25 but is positioned so that when a card is fed through the machine, electrical contact between the sensing element 18 and the conducting ring 25 is broken by the card. So long as there is no card in the machine, an electrical circuit will be maintained from the source of electrical potential 50 through the conducting wire 51, brush 27 to the ring 25 and then through the sensing element 18 to the electro-magnet 52 and back to the source of electrical potential through the wire 53.

This circuit energizes the electro-magnet 52 which draws and retains the armature 54 against the electro-magnet thereby breaking and holding apart the electrical contact 55. A card which is fed into the machine passes between the sensing element 18 and the conducting ring 25 breaking the electrical circuit to the electro-magnet 52 which deenergizes the electro-magnet and the armature 54 drops by gravity or may be repelled by a spring so that the contacts 55 are in contact with each other and in turn establishes an electrical circuit through the armature 54 until the card passes from beneath the sensing elements.

The electrical circuit controlled by the electro-magnet 52 and its armature 54 through the contacts 55 is the circuit through the sensing elements or means, which circuit will now be traced. Beginning from the source of electrical potential 50, the circuit passes through the wire 51 and the contacts 55 to the armature 54 and from the armature 54 through the wire 57 to the brush 21 also shown in Figure 1. As previously described, the brush 21 is in contact with the metal-

lic conducting surface of the roller 19 and establishes an electrical potential upon this roller. The sensing elements 16 are in contact with the roller 19 until a card passing through the machine breaks the contact but the circuit through the sensing elements is broken at contacts 55, as previously described.

Upon a card being fed into the machine, the card passes between the sensing elements 16 and the roller 19 breaking this electrical contact and the card also passes between sensing element 18 and ring 25 which closes contacts 55, as previously described, and establishes an electrical potential on roller 19. If now a perforation exists in the card in one of the perforation positions either regular or interspaced, the sensing element provided for the column having the perforation makes contact with the roller 19 through the perforation. Such a perforation 41a occurs in column 40a of the record card 1 and the sensing element 16a is shown in contact with the roller 19 through this perforation. This establishes an electrical circuit through the sensing element 16a which will now be traced.

The circuit from the source of electrical potential 50 to the roller 19 and the sensing element 16a has been previously traced. From the sensing element 16a, the circuit passes through the conducting wire 60 to a brush 61 which is in contact with a selector 80a, to be described in detail hereinafter, which establishes an electrical circuit between the brush 61 and the brush 62. The brush 62 is connected to one contact 64 of a plug socket, the ring 127 forming the other or ring contact.

A plug line shown in detail in Figure 8 is provided with a plug at each end. One of the contacts 65 of the plug line engages with the socket contact 64 when plugged in the socket which continues the circuit from the sensing element 16a through the wire 66 to the plug contact 67 at the other end of the plug line. The plug contact 67 is inserted in a plug socket consisting of the contact 71 which is engaged by the contact 67 and the ring 131. The socket contact 71 is connected through the wire 73 to the coil of a register control magnet 74a and the sensing means circuit is completed through the wire 75 to the source of electrical potential 50. This circuit controlling the first energizing of the accumulator control magnets may be termed the initial control circuit.

As the card 1 is fed down past the sensing elements an electrical circuit will be established between the respective sensing elements 16 and the conducting roller 19 wherever a perforation occurs in the columns of perforation positions. Such perforations will establish circuits identical with the circuit traced above so that a perforation occurring in a regular or numbered position of column 40b may be plugged-in to connect with and establish an electrical circuit through the coil of the accumulator control magnet 74b and a perforation in a regular or numbered position of the column 40c may be plugged-in to connect with and establish an electrical circuit through the accumulator control magnet 74c which circuits are identical to the circuit for the sensing element 16a described above. It is clear that the perforated designation in any regular position (as well as in any interspaced position which will be described) may be connected with any accumulator or counter merely by plugging-in to the proper plug sockets.

In tracing the circuit through the sensing ele-

ment 16a, the selector 80a was included as one of the connections of this circuit. Preferably the selector 80a is embedded in the surface of a roller 79 of insulating material as shown in Figure 6, 5 and is mounted to rotate with the shaft 33. A surface development of the selector 80a is shown in Figure 4. This selector is a serrated strip having the brush 62 contacting therewith throughout the length of the strip as it rotates. 10 Serrations 82 extend axially therefrom and the brush 61 is positioned to contact with these serrations or teeth. One such serration or tooth is provided for each perforation position for each 15 independent set of perforation positions in the columns excepting the last or zero position and therefore there are nine of such serrations 82 and not ten inasmuch as a perforation in zero position does not require reading or registering.

The selector 80a revolves at the same speed as 20 the feed roller 19 and is synchronized with the card feeding mechanism so that the serrations 82 establish electrical contact between the brushes 61 and 62 at the instant that the sensing element 16a comes into contact with one of the numbered 25 perforation positions in column 40a of the card 1. This selector therefore selects the perforations which are in the numbered perforation positions in column 40a and rejects any perforations which appear in the interspaced position. 30 A second selector 81a is provided adjacent to the selector 80a but insulated therefrom. This selector is identical with the selector 80a and has its serrations 83 extending between the serrations 82 in the selector 80a. This selector functions 35 in the same manner as the selector 80a, excepting that it selects the interspaced positions and rejects the numbered positions by establishing a circuit between brushes 61 and 63.

The selectors 80a and 81a together constitute a 40 distributor which distributes the electrical circuit set up by the sensing element 16a through a perforation record appearing in the numbered position in column 40a, to the accumulator control magnet 74a and the accumulator mechanism 45 controlled thereby, and distributes the perforation designation appearing in interspaced position in column 40a to the accumulator control magnet 94a and the accumulator controlled thereby which latter construction and circuit will be 50 described. One such distributor is provided for each perforation column on the card. The selectors are actually switches which open and close the circuits from the sensing elements 16 to the selected accumulator control magnets, such as the 55 magnets 74 and 94 respectively, as the sensing elements pass over the respective numbered perforation positions and the interspaced perforation positions and this invention contemplates any switching mechanism either mechanical or electrical which has this function. 60

Upon the sensing element 16a establishing electrical contact with the roller 19 through a perforation in one of the interspaces 42, such as perforation 43a shown in the interspace of column 65 40a for recording the number 7, an electrical circuit will be set up which will now be traced. This electrical circuit begins from the source of electrical energy 50 to the roller 19 over a circuit which has previously been described. The circuit will then pass through the sensing element 16a and the wire 60 to the brush 61, as previously described. The selector 81a rotates in synchronization with the card 1 as the card is fed past the sensing elements 16, therefore when the perforation 70 43a in interspace position of column 40a

passes under the sensing element 16a, the selector 81a will have rotated therewith so that one of the serrations 83 will establish electrical connection between the brushes 61 and 63. The circuit then continues from the brush 63 to the contact 5 85 of a plug socket. A plug-in line identical with the plug-in line 65, 66, 67 and therefore numbered to correspond therewith carries the circuit to the contact 81 of a second plug socket which connects by means of wire 93 with the coil of 10 electro-magnet 94a. The return circuit to the source of electrical potential 50 is made through the return wire 75.

Upon the accumulator control magnet 74a being energized the armature 100 is drawn into 15 contact with the coil or its armature thereby closing the contacts 101 and establishing a shunt or holding circuit which will be described. The holding circuit controls means to operate an 20 accumulator wheel. This operating means includes the arm 102, which is attached to the armature 100, is actuated upon the magnet 74a being energized which in turn slides the clutching element 103 along a constantly rotating shaft 104 so that the clutch tooth 105 upon the clutch member 102 engages one of the teeth 106 upon a 25 registering or accumulator wheel 107. The accumulator wheel or order 107 is loosely mounted upon the shaft 104 and normally remains stationary until engaged by the clutching element 103 which is keyed to the shaft so as to rotate therewith and still enable axial movement thereupon. The accumulator wheel 107 will rotate through so much of one complete revolution dependent upon the length of time that the clutching element 103 is in clutching engagement with the wheel. The accumulator wheel or order has numerals upon its circumference for registering the designations upon the cards. The spring 108 withdraws the clutching element 103 from engagement with the accumulator wheel 107 upon the circuit through the accumulator control magnet 74a being broken which deenergizes the magnet and releases the armature 100. 30 35 40

In the same manner as described above with respect to the designation represented by the perforation 43a being registered upon the accumulator counter 157, the designation represented by the perforation 43b in interspaced position in the column 40b may be plugged in to the coil of the 50 accumulator control magnet 94b and the perforation record 43c in column 40c may be plugged in to the coil of the accumulator control magnet 94c, or if desired any of these may be plugged in to connect with the coil of any accumulator control magnet. 55

The registering or accumulating mechanism per se described above is substantially old in the art and is included as an example of any accumulator means suitable for registering or accumulating the values represented by the perforations upon the record cards. Such accumulator mechanisms include also devices for carrying forward or transferring to the accumulator mechanism for the next higher digit 60 an advance of one unit when the lower digit mechanism has made one revolution and thereby accumulating the records. There are many such devices, one of which is shown in the Hollerith Patent 974,272. This mechanism is one of the 65 elements of the combination constituting the invention.

The accumulator control magnets 74 and 94 receive only a momentary energizing current from the circuit established by the sensing ele- 70 75

ments 16 projecting through perforations in the card since these circuits are broken preferably by the commutator immediately upon the perforation passing or even before the perforation passes the respective sensing element. A shunt or holding circuit is therefore provided through the accumulator control magnets which keep them energized for such periods of the cycle time as are determined by the perforation record on the 10 card so that the accumulator wheel is rotated as many units or digits upon its circumference corresponding to the number of the position perforated upon the record card.

As previously described, the energizing of the 15 accumulator control magnet 74a closes the contacts 101 which contacts establish a separate and distinct electrical circuit. Beginning from the source of electrical potential 50, this separate or shunt circuit is connected through the 20 wire 120 to a brush 121 which is in contact with a timing element 125 of a commutator 124, a surface development of which is shown in Figure 4, and its preferred form being shown in Figure 7. The timing element is mounted on the shaft 33 25 and rotates with the selectors 80 and 81. The commutator 124 comprises the metallic timing element 125 mounted upon a cylindrical insulating member. The timing means or element has three portions of varying circumferential length, 30 one of which extends entirely around the insulated cylinder and with which the brush 121 is continually in contact.

Brushes 122 and 123 are shown as positioned upon either side of the brush 121 and are also 35 shown in contact with the timing element 125 but upon portions which only partially pass around the insulated cylinder. So long as the brushes 122 and 123 are upon the metallic timing element 125, an electrical connection is established between the brushes 121 and 122 as 40 well as between the brushes 121 and 123 which electrical connections are broken when the brushes 122 and 123, during the rotation of the commutator, ride off of the conducting timing element and ride upon the insulating material. It will be noted that the brush 123 contacts with 45 the timing element for a longer period than the brush 122, the reason for which will be subsequently explained.

50 The shunt or holding circuit continues from the brush 121 to both brushes 122 and 123 through the timing element 125. The circuit through the brush 122 passes by wire 126 to a series of plug socket rings one of which is the 55 ring 121 forming the second contact of the plug socket which includes contact 64. The circuit then continues through the plug contact 68, the wire 69, the plug contact 70 and the ring 131 of the second plug socket, wire 132, through the 60 contacts 101, the coil of the electro-magnet 74a, and returning to the source of electrical energy through the wire 75. The shunt circuit is maintained then, so long as the electrical circuit is 65 maintained between the brushes 121 and 122 and so long as the contacts 101 are held together by the electro-magnet 74a.

The operative relation of the circuit through a 70 perforation in the card 1 and a sensing element 16 and the shunt circuit is as follows. The perforation in the card closes momentarily an electrical circuit through the sensing element 16 and the electro-magnet 74 which closes the contacts 101 establishing the shunt or holding circuit which shunt circuit continues to energize the 75 electro-magnet 74 until the shunt circuit is

broken at the timing commutator 124 by the brush 122 riding off of the conducting element 125 at the point 170 as the commutator rotates. Breaking of the shunt circuit deenergizes the electro-magnet 74 which releases the armature 100 and breaks the contacts 101 of the shunt circuit. The shunt circuit is opened thereby and the clutch 103 is also disengaged from the accumulating wheel 107. The breaking of the shunt circuit and the disconnecting of the accumulating wheel 107 from the rotating shaft 104, returns the entire mechanism to its original condition excepting the accumulator wheel and the mechanism is ready to register a second perforation in numbered or regular perforation position upon a second card.

Upon a perforation appearing in column 40a in interspaced position an exact duplicate shunt circuit, such as described above, is set up through the commutator brush 123. This circuit begins 20 from the source of electrical energy 50 and passes through the wire 120 to the brush 121 and through the timing element 125 to the brush 123 and wire 140 to the ring elements 141 of a series of plug sockets. A plug contact 68 is in 25 contact therewith which continues the circuit through wire 69 to a corresponding plug contact 70 which is in contact with the ring 143 of a second plug socket. The plug socket ring 143 is connected through wire 146 to the contacts 151 30 which contacts are controlled by the electro-magnet 94a.

The contacts 151 are open inasmuch as the sensing element 16a has not established an electrical circuit through an interspaced perforation. If interspaced perforation 43a were at the 35 sensing element 16a so that the sensing element would contact with roller 19, the electro-magnet 94a would be energized as previously described, which would close the contacts 151, establishing 40 the shunt circuit for the electro-magnet 94a. The energizing of the electro-magnet 94a raises the armature 150 which in turn moves the arm 152 and the clutching element 153 so that it 45 clutches with the accumulating wheel 157 in the same manner that the accumulating wheel 107 is coupled to the clutching element 103. The clutching element 153 is keyed to a constantly 50 rotating shaft 154 and the accumulating wheel 157 is rotated through a portion of a complete revolution determined by the position of the interspaced perforation in column 40a. This accumulating mechanism is identical in construction and operation with the accumulating mechanism associated with electro-magnet 74a. 55

The shunt circuit for the wheel 157 is broken by the brush 123 riding off of the timing element 125 at point 171 as the commutator 124 rotates which deenergizes the electromagnet 94a and restores the clutching element 153 out of 60 engagement with the accumulating wheel 157 and at the same time breaks the shunt circuit at the contacts 151. This restores the shunt circuit and the accumulating mechanism to its 65 original condition excepting as to the accumulating wheel, and ready to register a second record upon a second card.

The timing commutator 124 which constitutes 70 one of the elements of the shunt circuits is provided with a metallic element 125 which establishes electrical contact between the brushes 121 and 122 and between the brushes 121 and 123. This metallic timing element 125 controls the proportion of the cycle in which the shunt circuits to all of the accumulator control magnets 75

- 74 and 94 are energized dependent upon the manner in which they are plugged up. Inasmuch as the shunt circuit for a numbered perforation will be set up before the shunt circuit for a 5 perforation in the interspaced position for the same number is set up due to their relative position, this difference must be compensated for by the shunt circuit controlling the accumulators for the interspaced perforations being held an 10 equivalent longer period after the shunt circuit controlling the numbered perforation position has been broken. This is accomplished by maintaining the circuit between brushes 121 and 123 slightly longer than the circuit is maintained 15 between brushes 121 and 122 which result is obtained by extending the circuit breaking point 171 for the brush 123 slightly beyond the point where the circuit breaking point 170 of the brush 122 is placed.
- 20 Since the accumulator magnets governed by the regular designations receive their initial impulse in advance of those governed by the interspaced designations it follows that the accumulating wheels controlled by the regular designations will move forwardly slightly in advance of those controlled by the interspaced designations, and come to rest in advance of those controlled by the interspaced designations. The cycles of 25 primary adjustment for the two sets of designations therefore overlap but are not synchronous.
- 30 The shunt circuits described convert the designation, represented by the perforation in the column into a reading upon an accumulator by converting the position of the perforation upon 35 the card into an electrical impulse or current having a duration proportionate to the value or numeral represented by the perforation. The recording of the designation represented by the 40 perforations may also be said to be accomplished by the shunt circuit by converting the designation into a mechanical equivalent determined by the period of the cycle in which the accumulator control clutches are in driving engagement with the accumulating wheels.
- 45 The accumulator electromagnets 94b and 94c control duplicate accumulating mechanisms in the same manner that the electro-magnet 94a controls the accumulator wheel 157 and the associated shunt circuit so that a further description 50 of this duplicate mechanism is unnecessary.
- 55 In the description above, it has been pointed out that the two perforations in each column of the card are records or designations which are 60 separate and distinct from each other. The two 65 designations, however, represented by the two perforations may form separate digits of a multi-digit number. This may be accomplished by registering the designation represented by the 70 perforation in the interspaced position of column 75 40a upon the accumulating wheel 157, shown in Figure 5 as above described, and by registering the designation represented by the perforation in the numbered position upon the accumulating wheel 157b controlled by the electro-magnet 94b, so that the designation in interspaced position may represent the tens digit of a number and the perforation in numbered position may represent the units digit, or vice versa.
- 80 Similarly the perforations in column 40b of the card may represent respectively the hundreds digit and the thousands digit of a number and their value distributed to accumulator wheels having these respective positions.
- 85 This result is secured by merely inserting one

end of a plug-in line in the plug socket connected to the sensing element 16 which senses the perforations in the column having the desired designation and inserting the other end of the plug-in line in the plug socket connected 5 to the accumulating mechanism upon which it is desired to register the perforation record. This manner of plugging any sensing element into electrical circuit with any accumulating mechanism renders the construction shown herein very 10 flexible. In order to illustrate the flexibility of the construction of this invention, the last three columns 40a, 40b and 40c of the record card 1 may be plugged to the accumulating mechanisms so that three two-digit numbers are recorded or two three-digit numbers are recorded or a single six-digit number, or a four-digit number and a two-digit number which last may be obtained in several different ways which is 15 apparent.

20 It has been previously pointed out that the selectors 80 and 81 are simple switching means. The electrical circuit including this switching means is represented by the conductor 51, brush 21, roller 25, sensing brush 16, conductor 60, 25 brush 61, serration 82 of selector 80, brush 62, conductors to the electro-magnet 74, electro-magnet 74, and conductor 75. This electric circuit is broken at two points, namely, at the sensing brushes 16 by a card and at the selectors 80 30 and 81. The electric circuit is closed at the sensing brushes 16 when a perforation appears in the card 1 under a brush. The electric circuit is closed by the selector 80 every time that a serration 82 contacts with the brush 61. There 35 is one serration 82 for each regular position on the card and a space or insulator so far as selector 80 is concerned, between serrations. Obviously then the electric circuit above is closed so as to actuate the accumulator wheel electro-magnet 74 subject to two conditions, first, that a 40 perforation appear in the card 1 in the column controlled by the sensing brush and, secondly, that that perforation be in regular position. If the perforation is not in regular position upon 45 the card 1, the circuit is broken at the selector 80 and electro-magnet 74 is not energized.

50 Now the interspaced positions upon the card have a selector 81 identical with the selector 80. The selector 81 has a serration 83 for each identical interspaced position and a space or insulation so far as selector 81 is concerned, between the serrations 83. This selector 81 controls an electric circuit to electro-magnet 94 identical with the electric circuit for the electro-magnet 74 described above. The space or insulation between serrations is proportional to the space between identical perforation positions or perforation positions of the same series upon a record card such as the space between regular perforation positions. 60 In this way, like or identical series of perforations are selected for a particular electro-magnet circuit by the selector for that series and all other series of perforations are rejected. Since a plurality of perforation positions in columnar alignment is shown on the card and mechanism shown for selecting or distributing like series of perforation positions and rejecting others, the elements comprising one electric circuit may be multiplied 65 to accommodate for any number of series of perforation positions or independent records in columnar alignment upon a card. Incidentally, the serrations 82 and 83 upon the respective 70 selectors 80 and 81 are interspaced with respect to 75

each other merely for the reason that a single brush 61 may be utilized to serve both selectors.

Although the columns in the cards are shown as having but two perforations, it is clear that the system is applicable to a greater number of perforations. By merely adding duplicate accumulating mechanism, duplicate selectors or switching mechanisms which close a circuit through the brushes 61 and 62 and 61 and 63 for each of its positions upon the record card and associated mechanism to those shown and described herein, the additional perforations may be read and registered in the same manner as the two records or designations shown herein are read and registered.

Since the accumulating mechanisms are suitable for accumulating the data represented by perforations in either the numbered perforation positions or in the interspaced perforation positions which positions are half a space separated in each column, the clutching element must be capable of engaging the accumulating wheel irrespective of this half space difference and the resulting difference in time in which an electric circuit is set by a perforation in the numbered position and a perforation representing the same number in the interspaced position. The accumulator magnets governed by the regular designations or perforations, receive their initial impulse in advance of the initial impulse received by the accumulator magnets governed by the interspaced records. It follows, therefore, that the accumulating wheels controlled by the regular perforations will move forward slightly in advance of those accumulating wheels controlled by the interspaced records. Similarly, the accumulating wheels controlled by the regular perforations will come to rest in advance of the accumulating wheels controlled by the interspaced perforations. The cycles of primary adjustment for the regular and interspaced sets of perforations or designations therefore overlap but are not synchronous.

It may be said here that a sufficient number of teeth must be provided on the clutch members of the accumulating wheels or other means provided, so that the clutches will properly engage the wheels irrespective of whether a regular or interspaced designation is to be registered upon the accumulating wheel. Instead of providing the conventional ten clutch teeth, which would be one tooth for each digit position on the accumulating wheel, twenty teeth may be provided for example, as shown in Fig. 5, thus the clutch tooth 105 of clutching element 103 may engage the accumulating wheel 107 either when it is directly opposite an index number which occurs when controlled by a perforation in the regular perforation positions or when one-half way between two such numbers which occurs when the clutch tooth is controlled by a perforation in interspaced position. It is, of course, immaterial which tooth upon the accumulating wheel 107 the clutch tooth 105 engages since the tooth 105 can rotate the accumulating wheel through one or more digits, irrespective of whether it engages a regular tooth or an interspaced tooth. It is only essential that the accumulating wheel be rotated full digits and not half digits, irrespective of whether the clutch tooth 105 engages a regular or interspaced tooth on the accumulating wheel. When the clutch tooth 105 engages an interspaced tooth 107, the wheel is rotated a full digit or digits by the circuit 73 being broken a half turn early by the

brush riding off of the conductor 125 at the shoulder 110. Since the circuit was closed a half digit early because of an interspaced perforation, the circuit must be broken a half digit early in order to rotate the accumulating wheel a full digit or 5 digits. The structure of the conductor 125 and its function has been fully described hereinbefore.

In order that the columnar record of either or both the regular and interspaced record may 10 selectively be associated with and control any desired accumulating wheel in the machine, a plug board similar to that employed in a manually operated telephone exchange is provided. Since it is necessary that both the initial control circuit and the shunt holding circuit for each accumulator control magnet be associated with the proper brush 122 or 123 contacting with commutator 124, a double plug and plug socket is necessary. The shunt circuits could, of course, 20 go directly to the proper brush 122 or 123 contacting with the commutator 124 if the same set of accumulating wheels were always used to register records perforated in the regular positions, and another set of accumulating wheels 25 were always used for the interspaced records or perforations. Single circuit contacts then would be sufficient in the plug board, but in the interest of flexibility the arrangement shown is preferable.

30

The invention fully described herein is to be given a scope commensurate with the disclosure and it is to be understood that no limitations are intended by the specific means disclosed herein, excepting as set forth in the accompanying claims, and the word designation is intended to have a scope to include any system or method for recording data upon a record card or any equivalent thereof by perforating the card or otherwise providing a control device at a pre- 40 determined position or positions.

What is claimed is:

1. In a record controlled machine utilizing a record card having a plurality of designation columns and each column having a plurality of 45 sets of independent designation positions, said designation positions in each column being in columnar alignment and interspaced with respect to each other, the combination of means for sensing the independent designations in each 50 column of the card, an accumulator order for each set of independent designation positions, and means for distributing impulses derived from the sensing means upon contact with each independent designation to a different one of 55 said accumulator orders upon one passage of the card over the sensing means.

2. In a record controlled machine utilizing a record card having a plurality of columns of designation positions and each column having a 60 plurality of sets of independent designation positions, said positions being in columnar alignment and interspaced with respect to each other, the combination of sensing means for each column of designation positions for sensing the independent designations in each column, an accumulator order for each set of independent designation positions, a predetermined number of orders being positioned adjacent to each other 65 to form an accumulator to represent different digits of one number having at least two digits, and means for distributing the independent designations sensed by the sensing means in at least one column to adjacent orders of one ac- 70 75

cumulator and controlling the same to enter separate digits of a multi-digit number.

3. In a record controlled machine utilizing a record card having a plurality of columns of designation positions and each column having a plurality of sets of independent designation positions, the positions for each set being in columnar alignment and interspaced with respect to each other, the combination of means for each 10 column of the card for sensing the designations in each column, an independent electrical circuit for each set of independent designation positions in each column and controlled by the sensing means when it engages a designation, 15 means operable in timed relation to the passage of the card past the sensing means for establishing each circuit for its respective set of designation positions and breaking the circuit for each position of another set in the same column, an 20 accumulator or order for each independent designation in each column, and means controlled by its respective electric circuit for operating each accumulator order for entering thereupon the value of a designation on the card.
- 25 4. In a record controlled machine utilizing a record card having a plurality of sets of independent designation positions in each column of the card, said sets in each column being in columnar alignment and each set being interspaced 30 with another set of designation positions, the combination of a single sensing element for each column to sense each independent designation in each column of the card, an accumulator order for each set of designation positions in each 35 column of the card, means to operate each accumulator order when initiated by a designation in each column to register the value of a designation thereupon, and means provided for each single sensing element and connecting the latter 40 with one of the operating means for an accumulator order for each position of one set of independent designation positions upon the card as it is engaged by the sensing element and with another operating means for another accumulator order for each position of another set of 45 designation positions in the same column of the card as it is engaged by the sensing element, the said connection being made upon one passage of the card relatively to the sensing element.
- 50 5. In a record controlled machine utilizing a record card having a plurality of sets of independent designation positions in each column of the card, said sets of designation positions in each column being in columnar alignment with the 55 positions of each set being interspaced with respect to each other comprising, in combination, an accumulator order for each independent set of designation positions, operating means for each accumulator order to actuate the same and 60 enter the value of a designation thereupon, means for each of the aforesaid operating means and connected therewith to control its operation including an electric circuit for each independent set of designation positions in each column of 65 the record card; each electric circuit including sensing means to sense each independent designation in its respective column of the card, and a selector for each independent set of designation positions in its respective column of the card, each selector closing its respective electric circuit as the sensing 70 means passes over each designation position of its respective independent set of positions and breaking the circuit as the sensing means passes over other positions.
- 75 6. In a record controlled machine utilizing by a

record card having a plurality of sets of independent designation positions in each column of the card, said sets of designation positions in each column being in columnar alignment and the positions of each set being interspaced with respect to each other comprising, in combination, an accumulator order for each independent set of perforation positions, an electric circuit for each independent set of designation positions in each column of the record card connected with and 10 controlling the accumulator order, the electric circuits for each column including a single sensing element for that column to sense each independent designation in its column of the card, a selector for each independent set of designation 15 positions in each column of the card, each selector being connected in and closing its respective electric circuit as the single sensing element passes over each designation position of its respective set and breaking the circuit as the sensing element passes over other positions, and means connecting each of said electric circuits to a selected accumulator order of one or more accumulators to control the accumulator order by its selected designation and enter the value of the 20 designation thereupon.

7. In a record controlled machine utilizing a record card having a plurality of sets of independent designation positions in each column of the card, said designation positions in each column being in columnar alignment and the designation positions of each set being interspaced with respect to each other comprising, in combination, an accumulator order for each independent set of designation positions, an electric circuit for each independent set of positions in each column of the record card connected with and 30 controlling an accumulator order, the electric circuits for each column including a single sensing element for that column to sense each designation 35 in that column of the card, a selector for each independent set of designation positions in each column of the card, each selector being connected in and closing its respective electric circuit as the single sensing element passes over each designation position of its respective set of positions and breaking the circuit as the sensing element passes over other positions, and means connected with each of said electric circuits and a selected accumulator order of one or more accumulators to 40 control that accumulator order by the designation and enter the value of the designation thereupon, said last named means including means for each independent set of designation positions in one column of the card and common to the corresponding set of designation positions in all columns for entering the value of the designation upon the accumulator order.

8. In a record controlled machine utilizing a record card having a plurality of independent sets of designation positions in each column of the card, said positions in each column being in columnar alignment and the positions of each set being interspaced with respect to another set comprising, in combination, an accumulator order 60 for each set of designation positions, an electric circuit for each independent set of designation positions on the record card connected with and controlling an accumulator order, the electric circuits for the designations in one column including a single sensing element for that column to sense each independent designation in its column of the card, a selector for each circuit, each selector closing its respective electric circuit as the single sensing element passes over each designation 65 70 75 80 85 90 95 100

- tion position of its respective set of positions and breaking the circuit as the sensing element passes over other positions, and means for each accumulator order and initiated by closing of the aforesaid electric circuit for entering the value of a designation upon the accumulator order including a holding circuit for each accumulator order controlled by the closing of its respective electric circuit, the holding circuit including a timing element for each set of independent designation positions in one column of the card and common to the corresponding designation positions in all columns for breaking the holding circuit after a predetermined lapse of time.
15. 9. In a record controlled machine utilizing a record card having a plurality of sets of independent designation positions in each column of the card, said positions in each column being in columnar alignment and each set of positions being interspaced with respect to another set comprising, in combination; a feed roller to feed the cards into the machine; an accumulator order for each set of independent designation positions on the card; means operating each accumulator order to enter the value of a designation thereupon; and an electric circuit for each accumulator order connected with and controlling the operating means therefor, each electric circuit including sensing means for a column to sense each designation in that column of the card, and a selector for each set of independent designation positions in the column, each selector including a roller rotating at the same speed as the feed roller, a metallic strip on said roller, projections extending from the strip, the number of projections equaling the number of designation positions in each set of positions in one column of the card, and means cooperating with the metallic strip and the projections to close the electric circuit of which the selector is a part as the sensing means passes over each designation position of its respective set of independent positions and breaking the circuit as the sensing means passes over other positions.
45. 10. In a record controlled machine utilizing a record card having a plurality of sets of independent designation positions in each column of the card, said positions in each column being in columnar alignment and the designation positions of each set being interspaced with respect to the positions of another set, comprising, in combination, a feed roller to feed the cards into the machine; an accumulator order for each set of independent designation positions; means operating each accumulator order to enter the value of a designation thereupon; and an electric circuit for each accumulator order connected with and controlling the operating means therefor, the electric circuits for each column of the card having a single sensing means for these circuits to sense each designation in that column of the card; each electric circuit including a selector for each set of independent designation positions in each column of the card; each selector including a roller rotating at the same speed as the feed roller, a metallic strip on said roller, projections extending from the strip, the number of projections equaling the number of designation positions in each set in one column of the card, means cooperating with the metallic strip and the projections to close its respective electric circuit as the sensing means passes over each designation position of its respective set of independent positions and to break the circuit as the sensing means passes over other positions; an electrical holding circuit for each accumulator order and controlling the operating means therefor to enter the value of said designation upon the accumulator order including a commutator for all of said circuits and rotating at the same speed as the selectors, a metallic strip upon the commutator for each independent set of designation positions in one column of the card and common to corresponding sets of designation positions in all columns, and means cooperating with the strips to retain the holding circuit closed for a predetermined period to enter the value of designations upon the accumulator order.
11. In a record controlled machine utilizing a record card having a plurality of designation columns and each column having a plurality of sets of independent designation positions, said designation positions in each column being in columnar alignment and interspaced with respect to each other, the combination of means for sensing each column of the card for the independent designations in the columns of the card, an accumulator order for each set of independent designation positions, means for each set of designation positions and connected with a sensing means for distributing an impulse derived from the sensing means upon contact with one independent designation to an accumulator order for entering the value of the designation thereupon, the next aforesaid means distributing another impulse derived from the sensing means upon contact with another independent designation in the same column as the first designation to another accumulator order for entering the value of the designation thereupon, the second impulse being distributed while entering the value of the first designation on the accumulator order, the distributing of the impulses and the entering of the values of the designations occurring upon one passage of the card over the sensing means.
12. In a record controlled machine utilizing a record card having a plurality of designation columns and each column having a plurality of sets of independent designation positions, said designation positions in each column being in columnar alignment and interspaced with respect to each other, the combination of means for each column of the card for sensing the independent designations in each column of the card; an accumulator order for each set of independent designation positions; each column of the card being provided with means for distributing an impulse derived from the sensing means for that column upon contact with one independent designation to an accumulator order for entering the value of the designation thereupon, and means for distributing another impulse derived from the sensing means for that column upon contact with another independent designation in the same column to another accumulator order for entering the value of the designation thereupon, the latter impulse being distributed while entering the value of the first designation, the distributing of the impulses and the entering of the values of the designations occurring upon one passage of the card over the sensing means; and means for controlling each accumulator order after an impulse has been distributed thereto for a period commensurate with the position of the designation in the column and the set of designation positions in which the designation appears.
13. In a record controlled machine utilizing a record card having a plurality of designation columns and each column having a plurality of sets of independent designation positions, said designation positions in each column being in columnar alignment and interspaced with respect to each other, the combination of means for each column of the card for sensing the independent designations in each column of the card; an accumulator order for each set of independent designation positions; each column of the card being provided with means for distributing an impulse derived from the sensing means for that column upon contact with one independent designation to an accumulator order for entering the value of the designation thereupon, and means for distributing another impulse derived from the sensing means for that column upon contact with another independent designation in the same column to another accumulator order for entering the value of the designation thereupon, the latter impulse being distributed while entering the value of the first designation, the distributing of the impulses and the entering of the values of the designations occurring upon one passage of the card over the sensing means; and means for controlling each accumulator order after an impulse has been distributed thereto for a period commensurate with the position of the designation in the column and the set of designation positions in which the designation appears.

- sets of independent designation positions, said designation positions in each column being in columnar alignment and interspaced with respect to each other, the combination of means 5 for each column of the card for sensing the independent designations in each column of the card; an accumulator order for each set of independent designation positions; each column of the card being provided with means for distributing 10 an impulse derived from the sensing means for that column upon contact with one independent designation to an accumulator order for entering the value of the designation thereupon, and means for distributing another impulse derived 15 from the sensing means upon contact with another independent designation in the same column to another accumulator order for entering the value of the designation thereupon, the latter impulse being distributed while entering the 20 value of the first designation, the distributing of the impulses and the entering of the values of the designations occurring upon one passage of the card over the sensing means; and means for each designation in one column and common to 25 all columns of designation positions for controlling each accumulator order after an impulse has been distributed thereto for a period commensurate with the position of the designation in the column and the set of designation positions in which the designation appears.

14. In a record controlled machine utilizing a record card having a plurality of sets of independent designation positions in each column of

the card, said sets in each column being in columnar alignment and each set being interspaced with another set of designation positions, the combination of a single sensing element for each column to sense each independent designation in each column of the card, an accumulator order for each set of designation positions in each column of the card, means to operate each accumulator order when initiated by a designation in each column to register the value of a designation thereupon, means provided for each single sensing element and connecting the latter with one of the operating means for an accumulator order for each position of one set of independent designation positions upon the card as it is engaged by the sensing element and with another operating means for another accumulator order for each position of another set of designation positions in the same column of the card as it is engaged by the sensing element, the said connection being made upon one passage of the card relatively to the sensing element, and means controlling the operating means for the accumulator orders for a column so that one operating means continues to operate for a short period after another one has ceased operating in order to compensate for the designation in one set of designation positions initiating operation of an accumulator order prior to the initiation of another accumulator order by a corresponding designation in another set of designation positions in that column.

ROBERT L. HOUSTON.
